SNAP ACTION DEVICE
Sidney Taylor, Menlo Park, N.J., assignor to Wagner
Electric Corporation, a corporation of Delaware
Filed Apr. 26, 1965, Ser. No. 450,996
9 Claims. (Cl. 200—122)

This invention relates to an improved vane type snap action device and more particularly to an improved flasher particularly adapted for control of automobile signal lamps. The new device is relatively insensitive to load change and has excellent voltage response.

There have been many unsuccessful attempts, prior to applicant's invention, to solve the problem of constructing a flasher which is independent of load, maintains a sufficient speed of make and break during switching to insure little or no arcing between the contacts and has a low "figure of merit." The figure of merit, in a series type flasher is the ratio of the "on" period of the flasher at eleven volts to the "on" period of the flasher at fifteen volts. In a shunt type flasher, the figure of merit is the ratio of the "off" period of the flasher, that is, when the current through the lamps is insufficient to light the lamps, at eleven volts, to the "off" period of the flasher at fifteen volts. A perfect voltage response would be where the figure of merit (F.M.) is one. However, a device which has an F.M. of no greater than three is acceptable to automobile manufacturers.

Applicant's flasher satisfies all of the above requirements. Prior art flashers which were independent of load had limited life because of arcing between the contacts and flashers which had sufficient speed and force to prevent arcing did not function properly at different loads.

Applicant's invention provides a snap action device which has a low figure of merit, no detectable arcing between the contacts, will not drift from set tolerances after being in use for long periods of time and which can be made to operate independent of load.

As in prior art devices, for example that of Schmidinger Reissue Patent 24,023, applicant's device comprises a vane of thin resilient material and of any desired shape which has a deformation therein tending to cause the vane to curve or bend about one axis, and an expansible pull element which is connected at its ends under tension to the vane and which when cold holds the vane in a bowed or buckled position in which it is curved about one axis 90° from the axis of the deformation. In the prior art devices, the initial or inherent deformation has generally been introduced by bending the vane over a mandrel or by forming continuous or discontinuous ribs therein along one axis. The deformations in such prior art vanes caused the vane, before the ribbon was attached, to have a generally uniform curvature about the axis of deformation.

As distinguished from these prior art vanes, applicant's novel vane is so deformed that the curvature of the vane introduced by the deformation is maximum adjacent the periphery and minimum in the central area of the vane. This change in initial deformation results in the superior operation of applicant's device.

The initial deformation yielding the above described variations in curvature can be introduced by providing ribs on the vane which taper, either in depth or in width, from a maximum adjacent the periphery to a minimum in the central area.

The new vane is assembled to the flasher by first bowing or buckling the vane about an axis at right angles to the deformation formed by the ribs and then attaching a pull ribbon or wire to the sides of the vane to hold the vane in the buckled position.

The assembly of vane and ribbon is supported by a bracket attached either to the vane or to the ribbon. The

movable contact may be mounted either on the ribbon or on the vane. When the flasher is arranged for series operation, the contact is mounted on the vane if the support is attached to the ribbon and conversely if the support is attached to the vane, the contact is mounted on the ribbon. When the flasher is arranged for shunt operation, both the support and the movable contact may be mounted on the vane.

When the ribbon is heated, either by current flowing directly through it or by a heating coil, the ribbon will expand and the vane which is held in the buckled or constrained position by the ribbon will snap and return toward the position to which it is biased by the ribs. This tendency of the vane to oppose the tension of the pull ribbon and constantly seek to return to the position to which it is biased by the ribs is characteristic of the monostable type of vane to which this invention relates.

The reason for the improved operation of a flasher constructed with applicant's unique vane is not completely understood. It is believed however, that by tapering the ribs, the end areas of the vane become more rigid than the central portion of the vane. This prevents the end areas of the vane from bending as a result of the contraction of the ribbon before the central portion of the vane starts to move. The force generated by the contacting ribbon will first be directed to the weaker central portion of the vane causing the vane to move with sufficient speed and force to prevent arcing at the contacts. Further, the force necessary to buckle the vane is smaller than would normally be required since there is no waste of the force generated by the ribbon in bending the ends of the vane. Therefore, less heat is required at the ribbon resulting in lower current devices insensitive to load changes.

This theory also applies when the vane is in the buckled position and the ribbon starts to expand. The energy stored by the vane will be directed to the weaker central area of the vane because of the tapered ribs resulting in the necessary speed of break to prevent arcing at the contacts.

Although applicant's novel vane construction is adapted for use both in series type and shunt type devices, the presently preferred use of the vane is in a shunt type flasher utilizing a heater winding about the pull ribbon. In such type flasher, the contacts are normally open and when the circuit is closed, current flows through the heater to the load, the resistance of the heater being high enough to prevent illumination of the lamps when the load is a lamp load. The current through the heater heats the pull ribbon, causing it to expand and permit the vane to snap toward the position to which it is biased by the ribs. In this position, the contacts are closed and the heater is shunted. The full voltage is therupon supplied to the lamps and they light. The pull ribbon therupon cools and contracts and snaps the vane back into the contact open position. Applicant's novel vane, when used in this type flasher, insures the desired speed of make and break of the contacts and reduces the amount of heat necessary for snapping the vane.

In applicant's shunt type flasher, as above briefly described, the pull ribbon is attached at its ends to opposite edges of the vane and embossed platforms are formed in the vane adjacent the points of attachment of the ribbon to the vane. The platforms insure clearance for the heater winding when the ribbon is cold, allowing the heater to touch the vane in the area between the platforms when the ribbon is hot. This arrangement improves the figure of merit of the device.

By insulating the heater winding with a relatively thin film of material such as quartz which has high electrical insulating properties and also high thermal conductivity, the contact of the heater winding with the

vane insures rapid cooling of the pull ribbon by the relatively cooler vane, resulting in the vane returning quickly to the position wherein it is buckled about an axis 90° to the deformation introduced by the ribs. This permits operation at a lower average temperature and improves the figure of merit.

For a better understanding of the invention and of the advantages thereof, reference may be had to the accompanying drawings which illustrate preferred embodiments of the invention.

FIG. 1 is a plan view of a vane formed with ribs tapering in height.

FIG. 2 is a sectional view taken along line 2—2 of FIG. 1.

FIG. 3 is a plan view of a vane formed with a rib tapering in width.

FIG. 4 is a sectional view taken along line 4—4 of FIG. 3.

FIG. 5 is a plan view of a vane formed with interrupted ribs tapering in height and showing a ribbon mounted on and overlying the convex side of the deformation introduced by the ribs.

FIG. 6 is a sectional view taken along line 6—6 of FIG. 5.

FIG. 7 is a top perspective view of a vane formed with interrupted ribs tapering in width and showing a ribbon mounted on the vane and overlying the convex side of the deformation formed by the ribs.

FIG. 8 is a sectional view taken along lines 8—8 of FIG. 7.

FIG. 9 is a front view of a shunt type flasher incorporating a vane of the type of FIG. 1.

FIG. 10 is a rear view of the shunt type flasher of FIG. 9.

FIGS. 11 and 12 are exaggerated diagrammatic views showing the shunt type flasher in the "off" and "on" position, respectively.

FIG. 13 is a front view of a series type flasher incorporating a vane similar to the vane of FIG. 2.

FIG. 14 is a rear view of the series type flasher of FIG. 13; and

FIGS. 15 and 16 are exaggerated diagrammatic views of the series type flasher in the "on" and "off" position, respectively.

FIGS. 1 through 8 inclusive show various arrangements and constructions of the vane of the invention.

Referring to FIGS. 1 and 2, a rectangular vane 30 of a suitable resilient electrically conducting material such as spring steel is formed with tapering ribs 32 and with two small holes 34 symmetrically placed with respect to the short axis and lying along the long axis of the vane. Although the vane is shown in rectangular form, it is to be understood that any other configuration may be used without affecting the operation or merits of the vane.

The ribs are formed higher at the sides 36 of the vane and then gradually taper to a minimum height at the holes 34. The degree of taper will depend on the thickness of the vane, the material used to make the vane, and the operating current of the device in which the vane is used.

For flashers for twelve volt automobile circuits, a vane of one inch by one-half inch of spring steel with ribs tapering from a height of four or five and a half thousandths of an inch to three or three and a half thousandths of an inch is recommended although other combinations of rib height and vane dimension can be employed.

Although the provision of the two holes 34 is not essential as a single larger hole could be provided or the center of the vane could be imperforate, there are certain advantages in the provision of the two holes. In mass production, termination of a rib at a hole simplifies the tools required in the stamping operation. Also the two holes increase the weakening of the vane in the

central area which, as heretofore described, is advantageous in insuring rapid make and break. However, depending upon where a contact is to be mounted, it is advisable not to have the central section of the vane too weak. In a preferred embodiment of the flasher as will be described in connection with FIGS. 9 and 10, the movable contact is secured adjacent the longer side of the vane and in the central area of such longer side. The area of the vane intermediate the two holes provides the required strength in the central area to which the contact in the preferred embodiment is secured. A further advantage of the two-hole construction is that it permits the production machines to use aligning pins during the manufacturing process.

FIGS. 3 and 4 show a square shaped vane 38 provided with ribs 40 which are of uniform depth but are wider at the ends 42 of the vane 38 and taper to a minimum width at a central hole 44. Preferably, the width of each rib 40 at the outer end thereof is about one quarter or one third of the width of the vane and at the inner end is about one tenth of the width of the vane but wider or narrower ribs could be employed.

It will be noted that in the embodiment of FIGS. 3 and 4 there is only one hole 44 but two holes could be provided if desired.

FIGS. 5 and 6 show a circular vane 52 in which four ribs 54 having a tapered height are symmetrically placed about one diameter of the vane so as to form a deformation along the said diameter. In this arrangement, the ribs are formed as in FIG. 1 but terminate short of the periphery of the vane. The height of each rib 54 is maximum at its outer end and gradually tapers to a minimum in the central portion of the vane. A ribbon 56 is attached at its ends under tension to the periphery of the vane 52 and overlies the convex side of the deformation formed by the ribs and when cold holds the vane in buckled position, that is, bowed about an axis 90° to the axis of the deformation.

FIGS. 7 and 8 show an oval shaped vane 58 in which four ribs 60 are formed therein so as to form a permanent deformation along the minor diameter of the vane. The ribs are concave as viewed in FIG. 7, are of uniform depth but wider nearer the periphery of the vane, and taper to a zero width adjacent the central region of the vane. The ribs 60 are the type shown in FIGS. 2 and 3 except they do not extend to the edge of the vane or terminate at an opening in the vane. A ribbon 62 is attached at its ends to the periphery of the vane and overlies the minor diameter of the vane on the convex side of the deformation formed by the ribs.

In FIGS. 9 and 10, a shunt type flasher is shown having a vane of the type of FIG. 1. The vane 62 formed with ribs 64 of tapering depth is supported by a post 66 which is welded at 68 to the vane adjacent the center of a longer side thereof. The vane is formed with two embossed platforms 70 at opposite ends of a diagonal. A ribbon 72 overlies the platforms 70 and is attached at its ends to the corners of the vane. The ribbon overlies the vane on the convex side of the deformation caused by the ribs and when cold holds the vane bowed about an axis 90° to the direction of the ribs.

An insulated heating coil 74 is wound around the ribbon and fastened at one end to the ribbon or vane and at the other end to a post 76 which holds a stationary contact 77. It is important to use an insulation for the coil which will not make the wire so stiff that it is difficult to wind, will not be so brittle as to break, or so weak that it does not give sufficient insulation. Further, the insulation must be able to withstand constant heating and cooling without deteriorating. Also the insulation preferably should have high heat conductivity and low electrical conductivity. Applicant has found that a suitable insulation material for use on the coil is made from a polymer of amide-imide. The Amoco Co. sells this particular insulation under the service mark A1-220.

The embossed platforms 70 will prevent the coil 74 from contacting the vane when the vane is in the buckled position. However, the platforms 70 will not prevent the coil from contacting the vane between the platforms when the ribbon has expanded and the vane has snapped toward the position to which it is biased by the deformation. The coil being in contact with a larger cooler body will give up its heat rapidly, allowing the vane to return quickly to the buckled position. As explained before, rapid cooling improves the figure of merit. In the buckled position, when the coil is out of contact with the vane, most of the heat generated by the coil will be conducted to the ribbon. This increases the sensitivity of the flasher since a smaller current can be used for heating the coil.

A contact 78 is mounted on the vane 62 at a position where it will meet stationary contact 77 when the ribbon is hot. The post 66 which supports the vane 62 and the second post 76 on which the contact 77 is mounted is molded into a plastic base 80 by conventional methods.

When the flasher is arranged in a conventional automobile circuit, closure of the directional switch causes current to flow from the battery through post 66, vane 62, coil 74 and second post 76. In FIGS. 11 and 12 the battery connection is indicated at X and the load connection at L. As current passes through the coil, it heats the coil which in turn heats the ribbon until the ribbon expands sufficiently to allow the vane to snap to contact closing position. (See FIG. 12.) When the contacts are closed, current flows from the battery through post 66, vane 62, contact 78 mounted on the vane, contact 77 carried by post 66 and post 76. No current will flow through the ribbon or coil since the vane, which has virtually no resistance, will short the ribbon and coil allowing the ribbon and coil to cool. When the ribbon cools and contracts sufficiently, it snaps the vane at a 90° angle to the deformation formed by the ribs, opening the contacts 77 and 78. The alternate opening and closing of the contacts will continue as long as the directional switch is closed. The load or directional lamps of the automobile are arranged in relation to the flasher so that when the contacts are closed, the lamps are on, and when the contacts are open, there is insufficient current to cause the lamps to light.

A series type flasher is shown in FIGS. 13 and 14 incorporating a vane similar to the vane of FIG. 3. The vane 82 has a pair of ribs 84 of uniform depth and whose width are greatest at the ends 90 of the vane and are tapered to a point short of the center 92 of the vane. The ribs are concave as viewed in FIG. 13. A ribbon 94 is attached at its ends to the sides of the vane and extends parallel to the ribs. The ribbon is attached while the vane is bowed about an axis 90° to the longitudinal axis.

A post 96 is attached to the ribbon at 98 and supports the ribbon and vane. A second post 100 carries a fixed contact 102 which will meet with a contact 104 carried by the vane 82 when the pull ribbon is cold.

The series type flasher is arranged in the conventional automobile circuit so that when the directional switch is closed, current from the battery flows through post 96, ribbon 94, vane 82, contact 104 carried by the vane and contact 102 mounted on post 96 and post 100 (see FIG. 15). The current is sufficient to heat the ribbon to the point where its expansion permits the vane to snap toward the position to which it is biased by the deformation introduced by the ribs 84, opening contacts 102 and 104. When the contacts are open, no current flows through the vane or the ribbon and the ribbon will cool. With the cooling and attendant contraction of the ribbon, the vane will snap back into contact closing position. As with the shunt type flasher, the alternate opening and closing of the contacts, with the attendant turning off and on of the signal lamps, will continue as long as the directional switch is closed.

The invention has now been described with reference to various embodiments thereof. Although in each case

reference has been made to the snap action device of the invention as being a flasher for use in control of automobile directional signals, obviously the device may be employed for intermittently energizing any load or could be employed as a re-closing circuit breaker. In each embodiment of the invention illustrated in the drawings, ribs have been illustrated of tapering width or thickness for providing the inherent deformation in the vane. In all embodiments of the invention, the ribbon has been described as overlying the convex side of the inherent deformation occasioned by the ribs. In all figures, except FIGS. 7 and 13, the ribs are convex on the side of the vane over which the pull ribbon extends whereas in FIGS. 7 and 13 the ribs are described as concave toward the ribbon. It will be appreciated by those skilled in the art that the curvature introduced by the ribs depends not upon the direction in which the metal of the ribs is displaced from the surface of the vane but upon the configuration of the lips of the forming tools used to impress the ribs upon the vane. In other words, the inherent curvature introduced into the vane by the ribs depends upon the tool used in impressing the ribs on the vane and not upon the direction in which the metal of the vane is displaced.

Various changes in the specific constructions illustrated in the drawings can be made without departing from the spirit of the invention or the scope of the accompanying claims. For example, only in FIGS. 1 and 9 have two central holes been shown in the vane. Obviously two holes could be employed in the constructions illustrated in the other figures of the drawings or conversely the embodiments of the invention illustrated in FIGS. 1 and 9 could be provided with a single hole at the central region or with no holes. The same is true of the embodiments of the invention illustrated in FIGS. 5, 7 and 13. Also, although the ribs have been shown and described as tapering either in height or in width, obviously ribs tapering both in height and in width could be employed. Other variations will occur to those skilled in the art.

I claim:

1. In a snap action device for control of directional signals of automotive vehicles of the type wherein a deformed vane of resilient conducting material snaps back and forth between circuit controlling positions to interrupt the flow of current to the automobile signal lamps in response to expansion and contraction of a pull ribbon secured at spaced points to the vane, the improvement which comprises at least one rib formed in the vane the said rib being concave relative to one surface of the vane and convex relative to the second opposite surface of the vane and tapering in at least one dimension from a maximum adjacent the periphery of the vane to a minimum adjacent the central portion of the vane to provide a deformation in the vane along one axis which biases the vane to make it monostable and thereby cause it always to seek and assume one circuit controlling position when the pull ribbon expands, said vane snapping to a second circuit controlling position in which the vane is curved along an axis angularly disposed to said first axis and at opposite curvature to said first deformation when the ribbon contracts.
2. The improvement according to claim 1 wherein said rib tapers in height from points adjacent the periphery of the vane to the central area.
3. The improvement according to claim 1 wherein the rib tapers in width from points adjacent the periphery of the vane to the central area.
4. The improvement according to claim 1 wherein the vane is provided with two aligned ribs which terminate adjacent the central area of the vane and the vane is apertured at each such termination.
5. A vane type flasher for control of directional signals of automotive vehicles comprising a vane having a deformation therein tending to bow the vane about one axis, said deformation comprising a rib which is con-

cave relative to one surface of the vane and convex relative to the second opposite surface of the vane having a maximum dimension adjacent opposite portions of the periphery of the vane and a minimum dimension in the central area of the vane, the said deformation being effective to provide a bias in the vane which makes it mono-stable whereby it always seeks to return toward the position of the said deformation, a heat expansible pull means secured at its ends to parts of said vane adjacent the periphery and overlying the surface of the vane which is made convex by the deformation, said pull means when cold bowing the vane about an axis angularly disposed to said one axis and when heated permitting the vane to snap to opposite curvature about said one axis toward the position given to the vane by the said deformation, and means for intermittently heating said pull means.

6. The flasher according to claim 5 wherein said vane is rectangular, said rib extends parallel to one side and is of varying height.

7. The flasher according to claim 6 wherein the central area of said vane is provided with two spaced apertures, said rib being interrupted by said apertures and by the vane surface therebetween.

8. The flasher according to claim 6 wherein said vane 25 is provided with raised platforms adjacent two diagonally

opposite corners, the pull means passing over and engaging said platforms, and wherein said means for intermittently heating said pull means includes an electrically insulated heater coil wound about said pull means, said platforms spacing said heater coil from the vane surface 5 when the vane is bowed under the tension in the pull means and permitting the heater coil to engage the vane surface for rapid cooling when the pull means expands and the vane snaps to opposite curvature.

9. The flasher according to claim 8 wherein the heater wire is electrically insulated by a composition having high electrical resistance and high thermal conductivity.
